UNITED STATES PATENT OFFICE

2,334,771

MINING MACHINE

Robert K. Jeffrey and Sterling C. Moon, Columbus, Ohio, assignors to The Jeffrey Manufacturing Company, a corporation of Ohio

Application March 18, 1939, Serial No. 262,764

11. Claims. (Cl. 262—28)

This invention relates to a mining machine and particularly to an improved hydraulic control system for a mining machine.

An object of the invention is to provide a mining machine in which the feed rate of the kerf cutting mechanism is automatically adjusted to compensate for the load thereon thereby to prevent overloading of the driving motor for said kerf cutting mechanism.

Another object of the invention is to provide an improved hydraulic control system for a mining machine in which hydraulic means are provided to effect a feeding of the kerf cutting mechanism in which the rate of liquid supply to the hydraulic feeding mechanism is adjusted in accordance with the current flow in the driving motor of the kerf cutting mechanism to prevent overloading of said driving motor.

A further object of the invention is to provide an improved power operated hydraulic control valve.

Still another object of the invention is to provide a solenoid operated hydraulic control valve which is adapted to control the rate of fluid flow therethrough in accordance with the current flowing in an electrical circuit.

Another object of the invention is to provide a combined solenoid and mechanically operated hydraulic controlling valve adapted to vary progressively the rate of flow of hydraulic liquid therethrough.

Other objects of the invention will appear hereinafter, the novel features and combinations being set forth in the appended claims.

In the accompanying drawings,

Figs. 1, 2 and 3 placed end to end comprise a plan view of a mining machine incorporating the features of our invention;

Fig. 4 is a diagrammatic plan view of the mining machine illustrating various horizontal swinging cuts which can be made thereby;

Figs. 5 and 6 are diagrammatic elevational views of the mining machine showing several vertical positions of adjustment of the cutter bar;

Fig. 7 is a piping diagram of the preferred form of the hydraulic control system of our invention;

Fig. 8 is a sectional elevational view of the high pressure relief valve of the control system of Fig. 7;

Fig. 9 is an elevational view of the preferred form of the automatic volume control valve of the hydraulic control system of Fig. 7 showing its mounting on the mining machine frame in section;

Fig. 10 is a plan view of the valve of Fig. 9;

Fig. 11 is a sectional view taken on the line 11—11 of Fig. 9 looking in the direction of the arrows;

Fig. 12 is a sectional view taken on the line 12—12 of Fig. 9 looking in the direction of the arrows;

Fig. 13 is a sectional view taken on the line 13—13 of Fig. 9 looking in the direction of the arrows;

Fig. 14 is an enlarged sectional elevational view taken on the line 14—14 of Fig. 10 looking in the direction of the arrows;

Fig. 15 is a sectional view taken on the line 15—15 of Fig. 14 looking in the direction of the arrows, and also showing the manual operating mechanism therefor partly in section;

Fig. 16 is an enlarged detail view taken on the line 16—16 of Fig. 14 looking in the direction of the arrows;

Fig. 17 is a modified form of a hydraulic control system showing only the portion thereof which differs from the hydraulic control system of Fig. 7;

Fig. 18 is an enlarged sectional elevational view showing the structure of volume control valve of the control system of Fig. 17;

Fig. 19 is an enlarged view partly in section showing the structure of an adjusting mechanism of the pilot valve of the control system of Fig. 17; and

Fig. 20 is a sectional elevational view of a pilot control valve employed in the hydraulic system of Fig. 17.

The mining machine herein disclosed constitutes an improvement upon the mining machine disclosed in the application of Robert K. Jeffrey et al., Serial No. 206,448, filed May 6, 1938, entitled Mining machine, now Patent No. 2,263,779, dated November 25, 1941. It is to be understood that unless a contrary fact is indicated, the structure of the mining machine of the instant application follows the structure of the mining machine disclosed in more detail in said above mentioned patent.

It has been found in practice that there is a tendency for kerf cutting mechanism to overload the driving motor therefor under certain conditions, as the kerf cutting mechanism is fed into the coal while cutting a kerf either during a sumping operation or a swinging operation, the latter of which may be in either the horizontal or vertical plane or an inclined plane and may be effected either by swinging the cutter bar with respect to the supplemental frame or by swing-

ing the entire turntable with respect to the main frame.

The mining machine disclosed herein and constituting our invention operates automatically to control the feeding forces supplied to the kerf cutting mechanism in accordance with the load on the driving motor which drives said kerf cutting mechanism.

Referring particularly to Figs. 1, 2 and 3, which together comprise a plan view of the mining machine, and to Figs. 4, 5 and 6, which show the mining machine diagrammatically, it will be seen that said machine comprises a main frame 30 including a track mounted truck 31 provided with wheels 32 adapted to ride upon mine track rails 33.

Mounted upon the said truck 31 for adjustment about an upright axis is a turntable 34 adapted to be swung about said upright axis by a pair of oppositely acting hydraulic piston motors 35. Pivotedly mounted upon the turntable 34 for adjustment about a horizontal axis is a supplemental frame 36 formed by a housing 37 of an electrical driving motor 91 contained therein, to which is rigidly attached a gear housing 38 provided with an integral and downwardly sloping neck to which is journaled gear housing 39; that is, the motor housing 37, gear housing 38 and neck carrying housing 39 are all rigidly attached together to form the supplemental frame 36. Said supplemental frame 36 is pivotally attached to the turntable 34 by journal bearings 40, 41 at the rear end of said supplemental frame 36 and turntable 34.

Also forming a part of said supplemental frame 36 is a pair of spaced arms or brackets 41 between each of which arms 41 and the motor housing 37 there is trunnioned the housing of a hydraulic piston motor 42, the piston rod of which is journaled to the turntable 34. The hydraulic piston motors 42 are adjustable to swing the supplemental frame 36 about the horizontal axis provided by the journal bearings 40, thereby to adjust the elevation of the forward end of said supplemental frame 36.

The rear end of the main frame 30 forms a supporting platform 55 upon which is mounted an electric motor 43 which serves a number of purposes. Said motor 43 drives a hydraulic pump 44 of the hydraulic control system and also drives the wheels 32 of the truck 31 to tram the mining machine along the mine rails through an appropriate gear train including clutch shifting mechanism 45 which is adapted also to effect a driving connection from the hydraulic motor 46 to said wheels 32 to effect slow speed summing of the entire mining machine while cutting a kerf. That is, the clutch shifting mechanism 45 includes a shiftable clutch member 47 which is operable from operating handle 48 through a gear train including pivoted shaft 49, rod 50, bell crank 51, rod 52 and bell crank shifter 53 to effect a driving connection to the wheels 32 by way of reduction gears 54 either from the electric motor 43 when operating at a high speed during tramping or from the hydraulic motor 46 when operating at a low speed during summing.

Also mounted upon the platform 55 is an electrical cable reel mechanism 56 which winds in and pays out the electric cable for supplying current to electric motor 43 and which is driven by drive mechanism 57 including a control clutch 58 operable from appropriate operating mechanism including handle 59.

It is to be noted that the operating handles 48

and 59 are positioned at an operator's station at which there is an operator's seat 60 also adjacent to which is a brake handle 61 of a brake mechanism associated with the wheels 32 of truck 31. There is also mounted upon the platform 55 a steel draft cable mechanism 62 which may be operated from the electric motor 43 through an appropriate drive including gears 63 to aid in the summing action of the mining machine particularly when operating under difficult conditions or to anchor the mining machine in the mine against retrograde movement.

Also mounted on an upright plate at the forward end of the platform 55 is a two-way control valve mechanism 64 having two valves therein one of which is controllable to swing the turntable about its upright axis by controlling the hydraulic flow of fluid to hydraulic motors 35, the other of which is operable to control the hydraulic motor 46 to effect the summing of the entire mining machine along the track rails 33.

The outer end of the neck housing 39 terminates in and forms a turnover head 65. Mounted upon the turnover head 65 for swinging movement about an axis which is perpendicular to the plane thereof is a kerf cutting mechanism 66 comprising a flat elongated cutter bar 67 around which is adapted to move an endless cutter chain 68 carrying cutter bits 69. The cutter chain 68 is driven from a drive sprocket, in a manner well understood in this art, at the rear end thereof which drive sprocket is driven from the electric motor 91 (Fig. 7) contained within housing 37 through appropriate drive gearing which extends through the gear housing 38, neck housing 39 and turnover head 65. It may be stated that the sole function of the motor contained within housing 37 is to drive the cutter chain 68 of said kerf cutting mechanism 66.

To provide for controlled swinging movement of the kerf cutting mechanism 66 about its upright pivotal axis with respect to the turnover head 65, a pair of reversely operating hydraulic piston motors 70 is provided, the cylinders of which motors are pivotally attached to arms 71 which form a part of the turnover head 65. The piston rods of said motors 70 are pivotally attached to an operating bracket 72 which is rigidly attached to the cutter bar 67. It is thus manifest that by alternate reverse operation of the two motors 70 the cutter bar 67 may be swung in its own plane in reverse directions.

To provide for the swinging of the cutter bar 67 in a plane perpendicular to its own plane, particularly so that said cutter bar 67 may be horizontally positioned, for example in any of the positions illustrated in Figs. 5 and 6 of the drawings for different positions of adjustment of the supplemental frame 36, said cutter bar 67 is pivotally attached to the turnover head 65 on a transverse axis which is parallel to the plane of said cutter bar. To effect swinging movement of said cutter bar 67 transversely of its plane there is mounted on the turnover head 65 a hydraulic piston motor 73 the piston rod of which is attached to a sliding head 74 to which are connected operating arms 75 attached to opposite plates 76 which at their bottoms form a journal upon which the previously mentioned bracket 72 is journaled for swinging movement and which acts to support the kerf cutting mechanism 66 from the turnover head 65. It is evident that expansion and contraction of the hydraulic piston motor 73 will therefore produce a swinging movement of the cutter bar 67 in an

arc perpendicular to its own plane. It is thus to be noted that the cutter mechanism 66 may be adjusted for swinging movement with respect to the turnover head 65 about axes that are disposed at a right angle with respect to each other.

To provide for the turning over of the head 65 so that the cutter bar 67 may be adjusted to a bottom cutting position, as illustrated for example in Fig. 6 of the drawings, or to a top cutting position, as illustrated for example in Fig. 5 of the drawings, or to vertical or intermediate positions on either side of the longitudinal axis of the neck housing 39, the said neck housing 39 is journaled on the aforementioned integral neck of the supplemental frame 36 and is provided with means for rotating it through almost, but not quite, 360 degrees, including a rotary type of hydraulic motor 71 (see Fig. 2), which is adapted to rotate the neck housing 39 through appropriate gear reduction mechanism preferably including worm gearing.

It may be stated that between the neck and its housing 39 there is a stop means which prevents 360 degrees of rotation but which permits the adjustment of the cutter bar 67 to any of the aforementioned positions.

To provide for the flow of hydraulic fluid to the hydraulic motors 70 and 73 which, of course, rotate with the turnover head mechanism 65 and thus rotate with respect to the supplemental frame 36, flexible hose hydraulic conduits 78 are provided which wind upon winding reel 79 which is driven to rotate with the neck housing 39 by a driving cable 80.

It may additionally be pointed out that mounted on one side of the gear housing 38 of the supplemental frame 36 is a four-way hydraulic control valve 81 including four slide pistons which slide pistons are individually controlled by four operating handles 82 (Fig. 2) positioned at an operator's station adjacent the rear end of the supplemental frame 36 and attached to the motor housing 37. There is one handle 82 for operating each of the pistons of the four-way valve 81.

It may be stated that one of said handles and one of said slide pistons is individual to the two motors 70, another individual to the motor 73, another individual to the motor 77 and another individual to the motors 42. In other words, motors 42, 77, 70 and 73 are individually controlled by the handles 82 which control individual pistons of the four-way valve 81.

It may also be mentioned that the previously mentioned two-way control valve 64 which is carried by the rear platform 55 has two slide valves one of which is individual to the hydraulic motor 46 to control the summing of the entire mining machine and the other of which is individual to the hydraulic piston motors 35 for swinging the turntable 34, the latter of which is controllable from two positions, one of which is adjacent the control station where handles 82 are located, by virtue of handle 83 (Fig. 1), the other of which is controllable from the position near the operator's seat 60 by handle 84. This is desirable because during tramping of the mining machine through the mine it is sometimes necessary to swing the supplemental frame on the turntable 34, particularly while rounding curves in the mine. All of the hydraulic motors are controllable from the operator's station adjacent the handles 82, for this is the normal position of an operator while the machine is cutting a kerf in the mine.

As was previously pointed out, it is desirable to regulate automatically the feeding movement of the kerf cutting mechanism 66 and this is preferably done in inverse proportion to the ampere load on the driving motor 91 (Fig. 7) contained within housing 37. It is also preferred that this inverse proportion be limited to less than the entire range of ampere variation. In practice, the mechanism is preferably adjusted so that the cutter mechanism is driven at full speed until the current reaches approximately 85% of its full load rating, whereupon the feed rate of the kerf cutting mechanism is progressively decreased as the current of the driving motor increases until it is finally shut off at approximately 115% of its full rated value. It is, of course, to be understood that the above is merely illustrative of the preferred range and the range may be extended in either direction to any extent desired.

It is, of course, evident that with this automatic system the kerf cutting mechanism is operated at the maximum rate possible without undesirable overloading of its driving motor 91, which is the motor in housing 37, so that when easy cutting is encountered, the feed rate is increased and when hard cutting is encountered the feed rate is reduced. Furthermore, when the driving motor for the cutting mechanism is not operated at all, or is merely running light as when no cutting operation is being performed, the feed rate for adjusting the various hydraulic piston motors is at a maximum thus providing for a high rate of adjustment to position the cutter mechanism for kerf cutting.

The apparatus which provides for this automatic control as above set forth, is disclosed in detail in Figs. 8 to 16 of the drawings, which will now be described in connection with Fig. 7 of the drawings, which shows the preferred form of the hydraulic control system.

Referring first to Fig. 7 of the drawings, it is to be seen that the hydraulic control system comprises a tank or reservoir 85 for the hydraulic fluid or oil from which extends a feed pipe 86 leading to four reversely connected valves 87 interconnected to the hydraulic pump 44 from which valves 87 there extends a pressure pipe or conduit 88. The valves 87 are so connected that the pressure in the pipe 88 is always positive regardless of the direction of rotation of the reversible pump 44. In this connection it may be stated that driving electric motor 43 is of the reversible type so that the mining machine can be trammed in reverse directions and consequently the pump 44 is subjected to rotation in reverse directions, as shown in Fig. 1.

The pressure pipe 88 leads to and through a pressure relief and by-pass control valve 89, the detailed structure of which is disclosed in Fig. 8 of the drawings, and hereinafter described in full detail. From said pressure relief valve 89 the pipe 88 leads to the automatic volume control valve 90, the structure of which is disclosed in full detail in Figs. 9 to 16 of the drawings, and which is one of the important features of our invention.

As a general description, it may be stated that the automatic control valve 90 is operative to control the volume of fluid delivered to the operating hydraulic motors of the hydraulic system in accordance with the current flowing in the electric motor contained in housing 37 which is illustrated at 91 in Fig. 7 of the drawings.

Leading from the automatic control valve 90 is

pressure pipe or conduit 92 which delivers hydraulic fluid under pressure to the two-way control valve 64. The two-way control valve 64 is effective to control the selective feeding of hydraulic fluid in reverse directions to the hydraulic piston motors 35 and to the rotary hydraulic motor 46, there being, of course, an individual piston for the two motors 35 on the one hand and the motor 46 on the other.

It may be stated that, as described in complete detail in the above mentioned patent of Robert K. Jeffrey et al., the two motors 35 and the single motor 46 are capable of operation at the same time or individually due to the particular construction of the control valve 64.

There is provided a return pipe 93 which delivers excess or seepage fluid from control valve 90 to the reservoir 85. A return pipe 94 is also provided to return hydraulic fluid from the bypass control and pressure relief valve 89 to the reservoir 85.

It may also be mentioned that leakage drain pipes 95 and 97 are provided for the motor 46 and pump 44, respectively, to return any excess fluid, such as is received due to seepage past the bearings thereof, to the reservoir 85 by way of junction block 98; and return pipe 96 having two branches provides a return conduit from two-way valve 64 to junction block 98.

That portion of the hydraulic control system above described which is to the lower lefthand side of the line 99 in Fig. 7 of the drawings, is all mounted on the platform 55 and therefore is stationary with respect to the main frame of the mining machine. The portion of the system now to be described is mounted for adjustment with respect to the main frame and is carried by the supplemental frame 36 or some structure which is attached to move therewith.

Extending to the four-way control valve 81 is a pair of flexible hydraulic fluid conduits or hoses 100 and 101, of which the former is a pressure hose leading from the valve 64 and the latter a return hose which leads to the junction block 98 and thence to the reservoir 85. It may be stated that pressure is delivered to the hose 100 from the pressure pipe 92 without regard to the position of any of the slide valves of the two-way valve 64. Said conduits or hoses 100 and 101 lead to and from the four-way control valve 81 which is provided with four individual slide valves as above set forth, one of which is operated to control the motor 71, another of which is operated to control the two motors 42 in parallel, still another of which is operated to control the motor 73 and the fourth of which is operated to control the reversely connected motors 70.

To provide for the floating of the cutter bar 67 on its pivot, when positioned in a vertical plane which is desirable for the cutting of vertical kerfs while the mining machine is summing along a curved mine track, a by-pass valve 102 interconnects the conduits leading to the hydraulic piston motor 73 which in cooperation with an equalizing valve 103, also connected between said conduits, permits the floating of the piston in said motor 73 whenever valve 102 is open. As above described, the reel 19 provides for the rotation of the hydraulic piston motors 73 and 73 with the neck housing 39.

It is also evident, of course, that motors 70 must swing about the axis of the turnover head 65 which is parallel with the plane of the cutter bar 67. To provide for the continuation of the

fluid conduit during this swinging motion a pivotally mounted packed bearing 104 is provided which forms continuing paths leading to the motors 70 for various positions of adjustment of the cutter mechanism 66 with respect to the head 65.

Referring particularly to Figs. 9 to 16, inclusive, of the drawings, it is to be seen that the automatic control valve 90 comprises a main casting 105 of non-magnetic material which has an integral downwardly extending cylindrical portion 106 formed with spaced integral flanges 107, 108 upon which cylindrical portion 106 and between which flanges 107 and 108 is mounted an operating solenoid 109 contained within an insulating casing 110.

Removably attached to the top of the casting 105 is a valve casting 111 of non-magnetic material which has a bottom integral flange 117 by which it is attached to casting 105 by screws 118, sealed together by seal wires 119 and which is provided with a central longitudinally extending cylindrical bore 112. Substantially midway of the casting 111 is a chamber, orifice or passageway 113 which is formed by the bore 112 extending through a centrally disposed web 114. Above the web 114 there is a circumferential port 115 communicating with the chamber 113 and provided with a threaded opening 116 to which is threaded pressure pipe or conduit 88.

It is thus manifest that port 115 is the inlet or pressure port for delivering fluid under pressure to the chamber, orifice or passageway 113 which, it may be stated, is adjusted as to effective size so that the pressure drop across the same regulates by-pass control valve 89, as hereinafter described, to control the volume of fluid flow delivered to the pressure pipes 88 and 92 and thence to the hydraulic piston motors of the hydraulic control system. The structure of this port 115 and the connection to it is illustrated in detail in Fig. 12 of the drawings. Directly below the web 114 there is a circumferential port 117 communicating with the chamber 113 and provided with a threaded opening to which is threaded pressure pipe or conduit 92. It is thus manifest that the port 117 is the outlet or receiving port for receiving fluid under pressure from the chamber, orifice or passageway 113.

To provide an adjustment of the effective size of the chamber, orifice or passageway 113 there extends into the bore 112, a slidable piston 118 of non-magnetic metal, the upper part of which is preferably, but not necessarily, uniformly tapered at 119 and the extreme upper portion 120 of which is generally cylindrical and is provided with oil seal grooves 121 to reduce the liquid flow past said upper portion 120. The central portion of the piston 118 is formed as a shank 122 of reduced diameter which is normally positioned centrally of the chamber 113 thereby providing a maximum effective opening of said chamber 113 when the valve 90 is in its normal position of adjustment.

Directly below the shank 122 is a generally cylindrical portion 123 of the piston 118 which is provided with oil seal grooves 124 to restrict the flow of oil through the lower portion of the bore 112. Extending downwardly from the cylindrical portion 123 is a shank 125 which, at its bottom, is pivotally attached to a plunger 126 of magnetic material by a loose connecting pivot pin 127, which plunger extends downwardly into a central opening 128 in the casting 105.

within which opening 128 is a helical spring 129, the upper end of which abuts an integral flange of the plunger 126 and the bottom of which rests on a ledge 130 formed in said opening 128. The opening 128 is provided with another ledge 131 which stops downward movement of the plunger 126 under the influence of the solenoid 109.

It is, of course, evident that the spring 129 urges the piston 118 to the maximum valve opening position as illustrated in Fig. 14 of the drawings, and that current flowing in the solenoid 109 attracts the plunger 126 to pull it downwardly against the action of the spring 129 which, after a predetermined movement, progressively reduces the effective size of the chamber, orifice or passageway 113 by the progressive movement of the tapered portion 119 of piston 118 therethrough.

It is further manifest, that the effective size of said opening or passageway 113 is inversely proportional to the amount of current flowing in the solenoid 109 once the tapered portion 119 of piston 118 has entered said orifice or passageway 113. As previously suggested, in practice it is preferred that a current of substantially 85% of the rated current for the motor 91 will be required before any appreciable reduction of the effective size of chamber, orifice or passageway 113 is effected, and that said passageway will be completely closed when the current reaches approximately 115% of the rated value; the complete closing, of course, being effected whenever the upper portion 120 of said piston 118 enters the orifice or passageway 113, for it substantially completely fills it.

To provide for the manual adjustment of the automatic control valve 90 so that an operator may vary the action thereof, to reduce the feed rate but, preferably, not to increase the feed rate, without regard to its tendency to operate automatically, said valve mechanism is provided with manually operable mechanism including an operating handle 132 which is pivotally attached to a stub shaft 133 supported upon the valve casting 111 by a journal bearing 134 and journal bearing 135, the latter of which is formed in a removable cap 136 which is attached to said casting 111 by screws 137. A packing 138 is provided to prevent loss of hydraulic fluid from the valve 90 about the shaft 133. Keyed to said shaft 133 is an operating shipper 139 which cooperates with a groove 140 in a thrust collar 141 which bears against the top of the plunger 126. It is manifest that by moving the handle 132 upwardly the control piston 118 may be positively moved in a downward direction to reduce the feed rate as herein-after pointed out. If desired, collar 141 may be rigidly attached to shank 125 in which case the feed rate may be either increased or reduced manually, and this may be either with or without the automatic control provided by solenoid 109.

It may be stated that the forces acting on the piston 118 by virtue of the spring 129 and the solenoid 109 are relatively small as compared with the strength of an operator and may be at the maximum of the order of fifteen pounds. Consequently, an operator will have no difficulty in adjusting the piston 118 manually by the handle 132 without regard to the tendency of the automatic mechanism to adjust said piston 118.

It may be stated that the automatic control valve 90 is mounted adjacent the forward left-hand portion of the platform 55, as seen by reference to Fig. 1 of the drawings, and is carried

on a horizontal plate 142 (see Fig. 9), by virtue of a flange 143 formed as an integral part of the casting 105, which flange is attached to the plate 142 as by screws 144. The handle 132 extends forwardly through a slot in an upright plate 145 of said platform 55 so that said handle 132 is readily operable by the operator who controls the valves 64 and 81 from handles 83 and 82, respectively.

10 As seen by reference to Fig. 14 of the drawings, the central portion of the automatic control valve 90 provides a chamber 146 which will be filled with hydraulic fluid at all times due principally to seepage, which hydraulic fluid will act as a lubricant for the moving parts therein and in the opening 128.

15 In the top of the casting 111 there is formed a chamber 150 which communicates with the chamber 146 by way of passageway 151. Excess hydraulic fluid is drained from the top of the chamber 150 by previously mentioned return pipe 93 (see Fig. 13).

20 To dampen somewhat the action of the piston 118 we provide in association with the upper portion 120 thereof a dash-pot the structure of which is best seen by reference to Figs. 14 and 16 of the drawings. Said dash-pot is formed by a cylindrical bore 152 in the top of said upper portion 120 into which projects a piston 153 which is slightly less in diameter than the diameter of the bore 152, said piston 153 being formed as an integral portion of a plug 154 having enlarged portion 155 which is adapted to extend into and close the bore 112 formed in the extreme top portion of the casting 111. The plug 154 additionally has a top cylindrical portion 156 which is rigidly attached to a removable top plate 157, for example as by having a press fit therewith, which plate 157 is removably attached to the casting 111 as by screws 158.

25 To provide a control pressure conduit leading from the valve 90 to the high pressure relief valve 89 which is responsive to the pressure in the pressure pipe or conduit 82 which, of course, is the same as the pressure in the port 117, I provide a conduit which is formed by a vertical bore 159 seen by reference to Figs. 9 and 13 of the drawings, the bottom of which communicates with said port 117. The vertical bore 159 communicates with a transverse bore 160 to which is connected a pipe or conduit 161 which, as seen by reference to Fig. 7 of the drawings, leads to the pressure relief valve 89. As illustrated in Fig. 13 of the drawings, the top of the vertical bore 159, which 30 communicates with chamber 150, is closed by a threaded plug 162.

35 Referring particularly to Fig. 8 of the drawings, it will be seen that the pressure relief and by-pass control valve 89 comprises a casting or body 163 provided with a central cylindrical bore 164 within which is a control piston 165 moved downwardly by a relatively weak helical spring 166 which bears against a closure plug 167 for the bore 164.

40 In the bottom of the casting 163 is a transversely extending passageway 168 through which the two extensions of the pipe 88 are in direct communication. At the bottom of the bore 164 and at a position generally surrounding the piston 165 when the latter is in its normal position, is a chamber 169 which is connected to return pipe 94 by a passageway 170. A bore 171 provides a communicating passageway between the passageway 168 and the bottom of bore 164 thereby 45 to subject the bottom of the piston 165 to the

pressure in the passageway 168 which, of course, is the same as the pressure in the pipe 63. Bore 171 also communicates with a pressure gauge 172 (see Fig. 7) by way of conduit 173 which pressure gauge 172, of course, measures the pressure in the pressure conduit 88.

Interconnecting the bore 164, at a position above that assumed by the piston 165 during any operating condition, and the passageway 170 which leads to the drain pipe 94, is a passageway 174 leading to chamber 175 which in turn leads to passageway 176. An adjustable ball check valve 177 is provided in chamber 175 and will release upon a predetermined pressure in the bore 164 above the piston 165.

As was above pointed out, the pipe or conduit 161 communicates the pressure in the pressure pipe 92 and port 117 to the bore 164. Consequently, valve 89 acts as a high pressure relief valve in that whenever this pressure becomes excessive at any value which may be adjustably determined by the check valve 177, an example of which is 1200 pounds per square inch, the check valve 177 will operate to relieve this pressure and permit a flow of the hydraulic fluid to the return pipe 94. The flow of this high pressure fluid from the conduit 161 into the bore 164 is through a passageway 178 which has a very restricted area thereby causing an appreciable pressure drop whenever the fluid begins to flow through said passageway 178.

After the ball valve 177 has cracked and the high pressure fluid begins to flow to the return pipe 94 the pressure in the bore 164 above the piston 165 will fall below that on the bottom of said piston 165 due to said pressure drop through passageway 178 which will result in the fluid under pressure on the bottom of the piston 165 moving it upwardly against the action of the weak spring 166, to provide a direct communication between the bore 171 and the passageway 170 by way of chamber 169. This, of course, will provide a direct communication between the conduits 88 and 94 thereby providing a direct return path for high pressure fluid in the line 88 to the return pipe 94. Whenever the pressure in the pressure pipe 92 is returned to normal, check valve 177 will close and the parts of the high pressure relief valve 89 will be returned to their normal positions as illustrated in Fig. 10 of the drawings. Said valve 89 also has an important function as a by-pass valve, as hereinafter explained.

By reference to Fig. 7 of the drawings, it is to be noted that the solenoid 109 of the automatic valve control mechanism 90 is connected in series with the armature of the motor 91 which drives the kerf cutting mechanism. As a consequence, the automatic control valve 90 is adjusted in accordance with the amount of current flow in said kerf cutting driving motor 91.

In the operation of the mining machine incorporating the hydraulic control system above described, the reversible electric motor 43 may be connected by a direct mechanical drive to the wheels 32 of the mining machine for trammimg in reverse directions. Furthermore, the motor 43 whenever in operation drives hydraulic pump 44 of the hydraulic control system to provide pressure for said control system in the proper pressure conduits 88, 92 and 100 at all times. The hydraulic fluid under pressure as delivered by said pump 44 is employed for sumping the kerf cutting mechanism 66 while performing a sumping cut by driving the rotary hydraulic motor

46 which may be connected to drive said wheels 32, as aforescribed. During any sumping operation the cutter chain 68 of the kerf cutting mechanism 66 is, of course, driven by the electric motor 91 which is within the housing 37. As previously mentioned, the electric motor 91 does not drive any other portion of the mining machine.

During the performance of a sumping operation as above described, the current flow in the motor 91 also flows in the solenoid 109 of the automatic valve control mechanism 90. Said valve control mechanism 90 is preferably so designed and adjusted that until the current flow in said motor 91 is approximately 85% of its normal or rated value, the automatic volume control mechanism of valve 90 will be in its normal position, as illustrated in Fig. 14 of the drawings, under which condition the system operates to deliver a full volume of fluid to whatever hydraulic motor is being operated which, under the conditions now being described, is the sumping motor 46.

It is, of course, manifest that before any kerf cutting operation is to be performed, the cutter bar 67 must be adjusted to a desired position. This may be done with the motor 91 de-energized, or it may be done with said motor running light, under which conditions the automatic volume control valve 90 is not in operation and in no wise acts to restrict the volume of liquid delivered to any of the hydraulic motors. This preliminary adjusting of the cutter bar will probably call into play practically all of the hydraulic motors including motors 35 for swinging the turntable, motor 46 for moving the mining machine in its entirety forwardly or rearwardly at a slow speed, hydraulic piston motors 42 for adjusting the supplemental frame 36 about its horizontal axis with respect to the turntable 34, hydraulic piston motors 70 for swinging the cutter bar 67 with respect to the turnover head 65 in its own plane, hydraulic motors 73 for swinging said cutter bar transversely of or at right angles to its own plane, and rotary hydraulic motor 77 for turning over the head 65, neck housing and all parts rigidly attached to them.

In the performance of the sumping operation as previously mentioned, it is, of course, evident that the cutter mechanism 66 is in operation and driven by the electric motor 91 in housing 37 to drive the continuous cutter chain 68. The sumping operation may be performed in a horizontal plane which plane may lie anywhere between the top or roof of the mine room, for example as illustrated in dotted lines in Fig. 5 of the drawings, and the bottom or floor of the mine room, for example as illustrated in the full line position at the bottom of Fig. 6 of the drawings. Furthermore, a horizontal sumping cut may be made at any intermediate position between the two extreme positions above mentioned.

In a wide entry such as one where the distance between the ribs is approximately equal to twice the distance from the turntable axis to the outer end of the cutter bar, a continuous horizontal arcuate cut may be made on the turntable axis, as illustrated by the semi-circle in full line in Fig. 4. In entries not so wide the successive arcuate horizontal connecting cuts illustrated by the dotted lines in Fig. 4 may be made, the turntable and supplemental frame 36 being held in adjusted position relative to the stationary truck 31 for each such successive arcuate cut. The feed of the kerf-cutter on the turntable axis is

effected by means of the hydraulic motors 35, 35 and the horizontal kerf cut is on a relatively long radius. The feed of the kerf-cutter on its own pivot is effected by means of the hydraulic motors 70, 70 and the horizontal kerf cut is on a shorter radius.

In narrow entries it is preferred first to make a sumping cut by traction feed along the mine track. That is, the whole machine is moved along the mine track at feeding speed to cause the kerf-cutter to cut a kerf rectilinearly parallel to the mine track in continuation of one of the ribs of the mine entry. This is followed by arcuate feeding horizontally either on the turntable axis or on the pivotal axis of the cutter bar while the truck is stationary on the mine track. Finally, a rectilinear withdrawal cut is made by traction feed to finish the horizontal kerf along the opposite rib of the mine entry. During the rectilinear sumping and withdrawal cuts parallel to the mine track, the cutter bar is held rigidly connected to the supplemental frame 36 and the latter is held rigidly connected to the truck 31. Horizontal kerfs may be cut between the ribs of mine entries of various widths at any elevation between the floor and the roof.

Vertical or shear kerfs may be cut between the floor and roof of mine entries of various widths anywhere between the ribs thereof. For such shearing cuts the cutter bar is adjusted to a vertical plane by means of the rotary hydraulic motor 71 and the shear kerf completed by rectilinear sumping and withdrawal cuts parallel to the mine track connected by arcuate cuts either on the pivotal axis of the cutter bar or on the axis of the trunnions 40, 40 (Figs. 2, 5, 6), the sumping and withdrawal cuts being effected by traction feed or by movement of the whole machine along the mine track at feeding speed and the upright arcuate cuts being made either by the motors 70, 70 or the motors 42, 42, while the truck is stationary on the mine track.

Also for adjustment purposes preparatory to kerf-cutting, the cutter bar may be swung about its pivotal connection to the turnover head 65 by hydraulic piston motors 70 or about the horizontal pivotal connection between the supplemental frame 36 and the turntable 34 provided by the journal bearings 40 under the influence of the hydraulic piston motors 42.

It is to be noted that said hydraulic piston motors 42, 35, 70 and 73 are all of the double acting type so that they may operate positively in reverse directions by reversing the direction of flow of the hydraulic fluid thereto.

It is to be particularly noted that when any of the hydraulic piston motors such as motors 35, 42, 70, 73 or 40 are in operation, and the electric driving motor 91 which drives the kerf cutting mechanism 66 is in operation, and a kerf is actually being cut thereby placing a load on said motor 91, the automatic control valve 90 is effective to maintain the feed rate of the cutter mechanism 66 at a value such as to maintain the current, or in other words the load on the motor 91, within safe limits.

If, during the cutting of a kerf the operator desires to vary the automatic action of the automatic volume control valve 90 to decrease the feed rate of the kerf cutting mechanism 66, this may be done by his operating the handle 132 thereof, as above described.

The mode of control over the volume of hydraulic fluid delivered to an operating hydraulic motor under the control of automatic volume control

valve 90 is of utmost importance and one of its outstanding characteristics is that it is entirely independent of the pressure at which the hydraulic fluid is flowing to the operating hydraulic motor. As was above set forth, there is a predetermined position for the piston 113 of said control valve 90 for each current value between 85 percent and 115 percent of the rated load of motor 91. This, of course, means that orifice 113 has a predetermined effective size for every current value between the mentioned limits. This orifice 113 is so arranged that the pressure drop across it is proportional to its size and the volume of hydraulic fluid flowing through it and entirely independent of the pressure of the hydraulic fluid. This drop in pressure across orifice 113 is, of course, transmitted to piston 165 of valve 89 and employed to control the by-passing of hydraulic fluid thereby. That is, the hydraulic fluid pressure in port 115 is the same as the pressure below piston 165, and the hydraulic fluid pressure in port 117 is the same as the pressure above piston 165. The top of piston 165 also has added to the hydraulic fluid pressure, that of weak spring 166, which is usually of the order of twenty-five pounds per square inch of area of piston 165.

With piston 165 in the position illustrated in Fig. 8 of the drawings, the full output of pump 30 44 is delivered to pipes 88 and 92 and thence to whatever hydraulic motor is in operation. However, when the size of orifice 113 is restricted under the influence of a load on motor 91, as above described, this full volume of hydraulic fluid when flowing therethrough produces such a pressure drop that the pressure on the bottom of piston 165 is greatly in excess of that on its top which causes it to rise and allow a portion of the fluid to by-pass from conduit 88, bore 171, chamber 169, passageway 170 to return pipe 94. In actual operation, this piston 165 automatically operates to by-pass just enough hydraulic fluid to maintain the flow of hydraulic fluid through orifice 113 at a value to maintain the piston 165 in a condition of equilibrium whereby it by-passes just the required amount of hydraulic fluid at all times, delivering the rest to the hydraulic motor in operation to feed the mining mechanism 50 at a rate to keep the load on motor 91 within the above mentioned limits. Should the load on motor 91 increase at any time, the effective size of orifice 113 is, of course, reduced causing an increased pressure drop thereacross which lifts piston 165 higher to by-pass more hydraulic fluid, thus reducing the flow thereof through orifice 113 and to the hydraulic motor performing the work until said piston 165 is again in a condition of equilibrium.

Should the load on motor 91 decrease at any time, the effective size of orifice 113 is thereby increased causing a reduced pressure drop thereacross which causes piston 165 to move downwardly to reduce the amount of hydraulic fluid by-passed, thus increasing the flow thereof through orifice 113 and to the particular hydraulic motor doing the work until said piston 165 is again in a condition of equilibrium.

As above mentioned, this automatic action is independent of the pressure of the hydraulic fluid. However, valve 89, in addition to this by-pass control hydraulic fluid also has the high pressure relief control afforded by check valve 177, as above described. The automatic volume control valve 90 and by-pass control valve 89 thus coop-

erate to regulate the feed rate of the kerf cutter 66 or of the mining machine to maintain the load on motor 91 within safe limits.

Attention is now directed to Figs. 17 and 19, inclusive, of the drawings, in which there is illustrated a modified form of automatic volume control. It is to be understood that the hydraulic system of Fig. 17 is the same as the system of Fig. 7 except where a contrary condition is indicated. In general, it may be stated, that the principal difference is that automatic volume control valve 90 has been replaced by other mechanism including automatic volume control valve 225 and mechanism for operating it.

In the system of said Fig. 17 the armature circuit of the electric motor 91 has connected in series with it a solenoid 179 with which there is associated a plunger 180 which is connected to an adjustable helical spring 181 by a shaft 182. Shaft 182 is pivotally attached to an operating lever 183 pivoted at 184.

Associated with the lower portion of lever 183 is a pair of oppositely positioned cushioning spring abutments 185, the detail structure of which is illustrated in Fig. 19 of the drawings. Each of said spring abutments 185 comprises a casing 186 carrying a stop 187, and within which is mounted a slide piston 188 to which is attached an outwardly extending contact pin 189 adapted to contact the lever 183 after a predetermined pivotal movement thereof. Also, in the casing 186 is an adjustable cap 190 the position of which may be adjusted by adjusting screw 191.

Between the slide piston 188 and the cap 190 is a helical spring 192. It is manifest that by adjusting the cap 190 the tension on the spring 192 may be varied thus varying the amount of current that must flow in the solenoid 179 to adjust the position of the lever 183.

The lever 183 controls a pilot valve 193, the structure of which is disclosed in detail in Fig. 20 of the drawings. Said pilot valve 193 comprises a casing 194 provided with a central cylindrical bore 195 closed at one end by a plug 196 and having therein a slide piston 197 provided with an operating rod 198 which is attached to said lever 183 and extends from the bore 195 through a sealing gland 199. The pressure pipe 88 has a branch 88' which leads to the central portion of the bore 195 thereby providing hydraulic fluid under pressure at this position. Leading from the bore 195 is a pipe or conduit 200. Forwardly and rearwardly of the piston 197 are drainage ports which lead to pipe or conduit 201 which, in turn, is connected to the junction block 83 and thence to sump 85.

It is manifest from reference to Fig. 20 of the drawings, that with the piston 197 in its normal position, as illustrated, fluid pressure will not be supplied to the pipe 200 but said pipe 200 is free to drain fluid to conduit 201. However, when said piston is moved to the extreme right, as viewed in said Fig. 20, in response to a predetermined heavy current flow in solenoid 179, conduits 88' and 200 will be in communication through bore 195 to supply hydraulic fluid under pressure to said conduit 200 which leads to automatic volume control valve mechanism 225. When the current flow in solenoid 179 is below a predetermined value, piston 197 will be moved by the spring 181 to the left, as illustrated in Fig. 17 of the drawings, to permit a flow of fluid from pipe 200 to drainage pipe 201 as aforesaid.

The structure of the automatic volume control valve mechanism 225 is disclosed in Fig. 18 of the

drawings and comprises a casting 226 provided with a cylindrical bore 227 which at 228 provides an opening, chamber, orifice or passageway formed in a web 229 with which communicates an inlet port 230 having a threaded opening 231 to receive pressure conduit or pipe 88. The opening 228 leads to outlet port 232 provided with threaded opening 233 which receives pressure pipe or conduit 92. Slidably within the bore 227 is a piston 234 having a tapered portion 235 and a cylindrical portion 236 provided with oil seal grooves 237. A shank 238 of the piston 234 connects the tapered portion 235 and another cylindrical portion 239 which is also provided with oil seal grooves 240. Extending from the cylindrical portion 239 is a shank 241 around which extends a helical spring 242 one end of which rests against the cylindrical portion 239 and the other end of which abuts a plug 243. A seepage pipe or conduit 244 is provided to drain the bore 227 to the right of the cylinder 239, as viewed in Fig. 18 of the drawings.

The obvious similarity between the structure of the piston 234 of Fig. 18 of the drawings and the piston 113 of Fig. 14 of the drawings, and the cooperating parts including the similar chambers, orifices or passageways 113 and 228, respectively, make the mode of operation of the automatic volume control valve 225 obvious. It is, of course, evident, however, that the valve 225 is not operated directly by a solenoid but, on the other hand, is operated from pressure in the pipe 200 which is communicated to and acts upon the left-hand end of cylindrical portion 226 of the slide valve 234, as viewed in Fig. 18.

The principal operations of the hydraulic system of Fig. 17 are in general similar to those of Fig. 7, though not identical. The detailed operation is slightly different. In the system of Fig. 17 whenever the mining machine is performing any kerf cutting operation by the operation of any of the motors 35, 42, 46, 78 or 73, the current flow in the motor 91 flows through the solenoid 179 to energize it. Whenever this current reaches a predetermined value as determined by the adjustment of the spring 181, and the spring abutments 185, which, for example may be 115 percent of the rated load of said motor 91, pilot valve 193 is operated to connect branch conduit 88' and conduit 200 thereby supplying hydraulic fluid pressure to actuate the automatic volume control valve 225. Piston 234 is then moved to the right, as viewed in Fig. 18 of the drawings, to adjust the tapered portion 235 thereby reducing the effective size of orifice 228 through which flows the hydraulic fluid supplied to the pressure conduit 92 and to whatever hydraulic motor is performing the feeding operation of the kerf cutting mechanism 66. This action will take place until the by-pass valve 29 sufficiently reduces the flow through pipe 92 to reduce the feed rate of the kerf cutting mechanism 66 so that the load on motor 91 is reduced, for example, to 85 per cent of its rated load, whereupon pilot valve 193 is returned automatically to its balanced position with pipe 200 sealed by the right hand boss of piston 197 due to the fact that the reduced magnetic pull on plunger 180 now equals the pull thereon due to spring 181, which will stop the movement of piston 234 of automatic volume control mechanism 225 which will be locked in this position of adjustment and hold the piston 234 in this position.

It is, of course, evident that continued variations in the load on the motor 91 will cause continued operations of the solenoid 179 with resulting operation of the pilot valve 193 either to pro-

duce an additional decrease in the rate of fluid flow to the hydraulic feeding motor or to increase said feed rate, depending upon the rate of current flow in the solenoid 179. In short, piston 234 is moved by power under the control of solenoid 179 to such a position that the load on motor 91 is retained at a substantially constant value between variable limits which may be very close; or relatively wide, such as from 85 percent to 115 percent of its rated load.

To reiterate briefly, it is manifest that with either of the hydraulic control systems of our invention the hydraulic motors for adjusting the cutter bar 67 to any position of adjustment preparatory to the cutting of a kerf are supplied with a maximum volume of hydraulic fluid, thus insuring their rapid movement to the desired positions of adjustment which, of course, are effected without any load on the kerf cutting mechanism or upon its driving motor 91, since these adjustments will be effected ordinarily with the driving motor 91 de-energized, or under any conditions, operating appreciably short of its rated load.

Once a kerf cutting operation is started and throughout the continuous operation of any kerf cutting operation involving the action of any of the hydraulic motors which are employed to adjust the cutter bar 67 during the cutting of a kerf, the energy supplied to the driving motor 91 of the kerf cutting mechanism 66 is employed, for example, by feeding the current through a solenoid to control in an inverse manner the feed rate of the kerf cutting mechanism in accordance with the current flow in the driving motor 91, in the system of Fig. 7, and in the system of Fig. 17 to maintain the feed rate such as to maintain a substantially constant load on motor 91, within a variable range.

As was previously mentioned, in the system of Fig. 7, it is preferred that the fluid delivery to the hydraulic feed motor, whichever one it may be, is maintained at a maximum value until a predetermined load is placed on the motor 91 which, for example, may be 85 percent of its rated value, though any other setting may be effected. Thereafter, the feed rate of the kerf cutting mechanism is automatically adjusted to prevent an overloading of the driving motor 91 for the kerf cutting mechanism and it is preferred that when the motor 91 reaches a maximum safe permissible load which, for example, may be 115 percent of its rated load, or any other desired figure, the automatic volume control operates to shut off the feeding of the kerf cutting mechanism entirely. However, superposed upon this automatic feed control is a manual feed control whereby the feed rate of the kerf cutting mechanism may be taken over from the automatic to the manual at the instance of the operator.

In the system of Fig. 17 the fluid delivery rate to the hydraulic feed motor in operation is maintained at a maximum value until the load on motor 91 reaches a desired maximum which, for example, may be 115 percent of its rated value, though any other setting may be effected. Thereafter, the feed rate of the kerf cutting mechanism is automatically adjusted to reduce the load on motor 91 for said kerf cutting mechanism and when this load is reduced to any desired value, for example, to 85 percent of its rated load, or any other selected value, the feed rate of said kerf cutting mechanism is not further reduced. Should the load on motor 91 fall below 85 percent of its rated value due to the feed rate of the kerf

cutting mechanism, said feed rate is automatically increased until the load on said motor 91 reaches 115 percent of its rated load, but no more. In short, the feed rate of the kerf cutting mechanism is always automatically maintained at a value to keep a substantially constant load on motor 91 within desired limits which may be adjusted as desired.

While our improvements relate particularly to the automatic control of fluid-pressure motor mechanisms which feed the kerf cutter either rectilinearly parallel to the mine track or arcuately on the pivotal axis of the cutter bar or on the axis of the turntable, it should also be noted that the motor 91 is protected against being unduly overloaded or overloaded to such an extent as to cause it to be overheated or burned out. It has been found in practice that a pressure responsive relief valve around the pump of a fluid pressure system for kerf cutting machines does not act properly to protect the cutter chain driving motor.

The systems of control shown in the accompanying drawings, depend upon variation of the electric current passing through the cutter chain driving motor 91 to control a by-passing of hydraulic fluid in accordance with a pressure drop across an adjustable orifice which is independent of the pressure of the hydraulic fluid, but is directly responsive to the volume of hydraulic fluid flow, and therefore such systems of control are effective to act long before there is any tendency to overheat the motor 91. Moreover the variations in the volume flow of the pressure medium to the various hydraulic motors are gradual and extend over a wide range.

In starting a shearing cut the operator may effect a slow starting feeding forward of the kerf cutter under control of the manual lever 132 of Figs. 7, 9 and 10, independently of automatic control effected by the current through the motor 91 and the solenoid 109. This enables the operator to work the kerf cutter slowly into cutting action after which the automatic volume control takes over the control.

It will thus be seen that the efficiency of operation may be safely maintained at a maximum in that the electric motor 91 for driving the chain cutter may be continuously and safely operated at its full load capacity or any other predetermined setting, so that when easy cutting is encountered, the rate of feed is automatically increased, and when the cutting is hard the rate of feed is automatically reduced. Moreover, when no cutting is taking place and the driving motor 91 is running free or is not operating, the rate of feed for adjustment of the kerf cutter relative to the supporting framework, is automatically raised to a maximum. If the current to the motor 91 is cut off during such adjustments of the kerf cutter, the spring 181 in Fig. 17 moves the piston 197 to the left, as viewed in Fig. 20, to permit the pipe 200 to be connected to the drainage pipe 291, whereupon the spring 242 (Fig. 18) is free to move the piston 234 to such position that the volume control valve 225 will be in its widest open position for maximum flow of the fluid pressure medium to the adjusting motors.

Obviously those skilled in the art may make various changes in the details and arrangement of parts without departing from the spirit and scope of the invention as defined by the claims hereto appended, and we therefore wish not to be restricted to the precise construction herein disclosed.

Having thus described and shown an embodiment of our invention, what we desire to secure by Letters Patent of the United States is:

1. In apparatus of the class described, the combination with a frame, of cutting mechanism mounted thereon, a motor for driving said cutting mechanism, fluid pressure mechanism for feeding said cutting mechanism, a volume control valve for controlling the rate of fluid flow to said fluid pressure mechanism, means responsive to the load on said motor for adjusting said control valve and thereby adjust the volume of fluid delivered to said fluid pressure mechanism to adjust the feed rate of said cutting mechanism, and means operable independently of said load responsive means for adjusting said volume control valve whereby the feed rate of said cutting mechanism may be manually or automatically controlled.

2. In apparatus of the class described, the combination with a frame, of cutting mechanism mounted thereon, motor operated mechanism for driving said cutting mechanism, motor operated means responsive to variations of load on said driving mechanism to regulate the rate of feed to maintain said load substantially constant, and manual means for controlling said last-named motor operated means independently of the load on said driving mechanism to decrease but not to increase the feed rate of the cutting mechanism at the will of the operator.

3. In apparatus of the class described, the combination with a cutting mechanism, of hydraulic means for feeding said cutting mechanism, a driving electric motor for said cutting mechanism, mechanism for feeding hydraulic fluid to said hydraulic feeding means including a valve having an orifice through which hydraulic fluid flows to said feeding means, means for adjusting the effective size of said orifice to a predetermined value for each value of current flowing to said electric motor which effective size is inversely proportional to said current, and mechanism for delivering hydraulic fluid to said hydraulic feeding means as determined by the pressure drop through said orifice.

4. In apparatus of the class described, the combination with a cutting mechanism, of hydraulic means for feeding said cutting mechanism, a driving electric motor for said cutting mechanism, mechanism for feeding hydraulic fluid to said hydraulic feeding means including a valve having an orifice through which hydraulic fluid flows to said feeding means, means for adjusting the effective size of said orifice including a tapered piston which is under the control of current flowing to said electric motor, the effective size of said opening being inversely proportional to the value of said current and mechanism for delivering hydraulic fluid to said hydraulic feeding means as determined by the pressure drop through said orifice.

5. In apparatus of the class described, the combination with cutting mechanism, of a hydraulic motor for feeding said cutting mechanism, an electric motor for driving said cutting mechanism, mechanism for delivering hydraulic fluid to said hydraulic motor at a rate controlled by the current flow through said electric motor to maintain the load on it within safe limits including a valve having an orifice, means including a tapered piston in said valve orifice adjustable to a predetermined position in accordance with the current flow through said electric motor whereby the effective size of said orifice is in-

versely proportional to said current when the current is within the range of 85% to 115% of the full rated current of said electric motor, and a volume control for the hydraulic fluid delivered to said hydraulic motor operated by the pressure drop across said orifice.

6. In apparatus of the class described, the combination with cutting mechanism, of a hydraulic motor for feeding said cutting mechanism, an electric motor for driving said cutting mechanism, mechanism for delivering hydraulic fluid to said hydraulic motor at a rate controlled by the current flow through said electric motor to maintain the load on it within safe limits including a valve having an orifice, means including a tapered piston within said orifice adjustable in accordance with the current flow through said electric motor, and a volume control for the hydraulic fluid delivered to said hydraulic motor operated by the pressure across said orifice.

7. In apparatus of the class described, the combination with a main frame, of a cutter mounted thereon, an electric motor for driving said cutter, hydraulic motor means for feeding said cutter, a hydraulic system including a pump for feeding hydraulic fluid to said hydraulic motor, valve means for by-passing a variable amount of the hydraulic fluid output of said pump and delivering the rest to said hydraulic system for operating said hydraulic motor means, mechanism in said hydraulic system responsive to the volume of hydraulic fluid flowing to said hydraulic motor means and interconnected to said valve means for controlling the rate of by-pass thereof, and mechanism responsive to the current flow through said electric motor for adjusting said first mentioned mechanism, said first mentioned mechanism including an orifice, a conical piston movable thereinto to vary its effective size, means urging said piston to maximum orifice opening position, and solenoid means opposing the action of said urging means and acting directly on a plunger connected to said piston through which solenoid the current to said electric motor flows.

8. In apparatus of the class described, the combination with a main frame, of a cutter mounted thereon, an electric motor for driving said cutter, hydraulic motor means for feeding said cutter, a hydraulic system including a pump for feeding hydraulic fluid to said hydraulic motor, valve means for by-passing a variable amount of the hydraulic fluid output of said pump and delivering the rest to said hydraulic system for operating said hydraulic motor means, mechanism in said hydraulic system responsive to the volume of hydraulic fluid flowing to said hydraulic motor means and interconnected to said valve means for controlling the rate of by-pass thereof, and mechanism responsive to the current flow through said electric motor for adjusting said first mentioned mechanism, said first mentioned mechanism including an orifice, a conical piston movable thereinto to vary its effective size, means urging said piston to maximum orifice opening position, hydraulic mechanism for adjusting said piston against said urging means including a pilot valve, a solenoid for adjusting said pilot valve and connected in series with said electric motor, and a spring opposing the action of said solenoid.

9. In apparatus of the class described, the combination with cutting mechanism, of a hydraulic motor means for feeding said cutting mechanism, an electric motor for driving said cutting mechanism, a pump, conduit means for

delivering hydraulic fluid from said pump to said hydraulic motor means while continuously bypassing a portion of the hydraulic output of said pump, passageway means in said conduit for restricting the flow of fluid supplied to said hydraulic motor, mechanism for adjusting the effective size of said restricted passageway to a pre-determined value determined by the value of the current flowing to said electric motor and variable inversely with variations in said current, and mechanism controlling said by-passing means as determined by the pressure drop across said restricted passageway.

10. In apparatus of the class described, the combination with a main frame, of a cutter mounted thereon, an electric motor for driving said cutter, hydraulic motor means for feeding said cutter, a hydraulic system including a pump for feeding hydraulic fluid to said hydraulic motor, valve means for by-passing a variable amount of the hydraulic fluid output of said pump and delivering the rest to said hydraulic system for operating said hydraulic motor means, mechanism in said hydraulic system responsive to the volume of hydraulic fluid flowing to said hydraulic motor means and interconnected to said valve means for controlling the rate of by-pass thereof, and mechanism responsive to the current flow through said electric motor for adjusting said first mentioned mechanism, said first mentioned mechanism including an orifice, a piston movable thereinto to vary its effective size, means urging

said piston to maximum orifice opening position, and solenoid means opposing the action of said urging means and acting directly on a plunger connected to said piston through which solenoid 5 the current to said electric motor flows.

11. In apparatus of the class described, the combination with cutting mechanism, of hydraulic motor means for feeding said cutting mechanism, an electric motor for driving said cutting mechanism, a pump having an output in excess of the normal fluid consumption of said hydraulic motor means, conduit means for delivering hydraulic fluid from said pump to said hydraulic motor means, a fluid by-pass control valve 15 in said conduit means constructed normally to by-pass a portion of said hydraulic fluid during operation of said pump and hydraulic motor means, and mechanism operable by variations of the rate of current flow to said motor to control 20 said by-pass valve to increase the fluid by-passed whenever said electric motor is over-loaded and to decrease the fluid by-passed whenever said electric motor is operating below its rated load whereby said electric motor is automatically 25 maintained in operation substantially at its full rated load, said by-pass control valve having an orifice, and said last-mentioned mechanism including a tapered piston extending into said orifice.
